UNITED STATES PATENT OFFICE

AUGUST GERARD, OF READING, AND MAURICE WEISMAN, OF BRIGHTON, MASSACHUSETTS, ASSIGNORS, BY DIRECT AND MESNE ASSIGNMENTS, TO COTTON-WOOD PRODUCTS, INC., OF READING, MASSACHUSETTS, A CORPORATION OF MASSACHUSETTS

FIBER PRODUCT

Application filed May 9, 1928. Serial No. 276,303.

This invention relates to fiber products having cushioning or insulating characteristics, and to methods of making such products.

5 One object of the invention is to produce cushioned pads for use in the covers of candy boxes and the like.

10 Heretofore, efforts have been made to manufacture cushion pads, and the like, from wood pulp fiber in a simple and inexpensive manner, but difficulties have been experienced in making an adequate, coherent and rugged pad, owing to the short lengths of the fibers and the difficulties of joining the fibers together in such a manner as to produce the 15 desired resiliency.

20 An object of the present invention is to overcome these difficulties and to provide an efficient, durable and easily constructed cushioned pad or insulating product of much lower cost than that of the usual cushioned products now available.

25 Another object is to make out of waste paper or similar fibrous material, cushioning or insulating products adapted for use as cushioned pads, thermal insulation, acoustical insulation, packing, sheathing paper and related uses.

30 In accordance with one aspect of the present invention, old newspapers, or other waste papers, or similar materials, hereinafter referred to as paper, are beaten while dry, into relatively small particles consisting of separate fibers of substantially completely disintegrated paper and of small flakes of incompletely disintegrated paper having a greater maximum length than that of said fibers. 35 These particles are produced in such proportions that when thoroughly intermingled, the fibers form a soft wadding between the flakes, and the resulting combination consists of flakes dispersed throughout the soft wadding in interlocking relationship therewith.

40 A laminated product having cushioning and insulating characteristics may be made by depositing a cementitious material on one surface of a piece of sheet fabric, depositing the above referred to flakes and fibers as a cushioning layer on the resulting cementitious 45 surface, and pressing the particles so depos-

ited into cementing relationship with the fabric.

In one species of the invention, the cushioning particles are deposited as a stream between two confluent sheets of fabric having cementitious material on their inner surfaces, thereby producing a cushion layer between the two fabric layers. The resulting laminations are then split medially of the intermediate cushioning layer to produce two 55 separate laminated sheets, each having a fabric layer and a cushioning layer cemented thereto. The cleavage surfaces, exposed by the fissure in the cushioning layer, are given a deposit of minute droplets of cementitious 60 material and are then restored into face to face contact and cemented together. 65

These and other objects and features of the invention will be understood more clearly from the following detailed description in 70 connection with the appended drawings, in which:

Fig. 1 is a schematic perspective view of one form of apparatus adapted for making the product of the present invention, the 75 front sides of portions of the apparatus being removed to expose to view the interior thereof, and portions being shown in cross section.

Fig. 2 is an enlarged plan view of a typical 80 fibrous flake produced by disintegration of dry paper.

Fig. 3 is an enlarged cross sectional view of the flake of Fig. 2.

Fig. 4 is an enlarged view showing a plurality of separate fibers of substantially completely disintegrated paper. 85

Fig. 5 shows on a larger scale, an axial section of a portion of the disintegrator rotor of Fig. 1. 90

Fig. 6 is an enlarged perspective view of a finished cushioned pad or insulating product.

Fig. 7 is a perspective view showing a modification of a portion of Fig. 1, adapted 95 to provide a fabric layer between two cushioning or insulating layers.

Fig. 8 is an elevation of a different type of machine from that of Fig. 1, portions of the machine being shown in section, and the 100

front frame of the machine being removed in order more clearly to expose to view the details of the machine.

Fig. 9 shows on a larger scale, an axial section of the disintegrator rotor of Fig. 8.

Fig. 10 is a side view of one of the hammers shown in Fig. 9.

Fig. 11 is a perspective view of a modification of apparatus for producing droplets of cementitious material.

Referring to Fig. 1, paper, such as waste paper and particularly old newspapers or other fabric of similar character, are deposited while substantially dry into the receiving hopper 1, from which the paper feeds to the disintegrator 2, of the beater type, having the rotor shaft 3, upon which are mounted the radial disks 4, keyed fast to the shaft. Bolts 5, mounted in equally spaced relation near the periphery of disks 4, support the metal hammers 6, preferably of rectangular block shape, which are free to swing independently of each other on bolts 5, as an axis, and are preferably made of wear-resisting material such as cold rolled or hardened steel, for example.

Shaft 3 is rotated at high speed by any suitable source of power not shown, the speed being preferably several thousand revolutions a minute so that hammers 6 tend to assume positions radial to shaft 3, as a result of the centrifugal force. The rapid rotation of rotor 3 disintegrates the paper by beating it and tearing it into relatively small fragments consisting of flakes 60 such as shown in Figs. 2 and 3, and separate fibers 61, Fig. 4. The flakes ordinarily have numerous small partially freed fibers extending therefrom, as shown in Figs. 2 and 3. The separate fibers 61, shown in Fig. 4, consist of substantially completely disintegrated paper, and are so short that they do not combine with each other with very appreciable coherency when intermingled with each other.

The separate fibers and all the flakes below a predetermined size are selected by sifting them through the screen 7 in the base of the disintegrator. The openings through screen 7 are so chosen that the flakes passing therethrough are relatively small, but have a maximum length greater than that of the fibers 61. In an actual practical case, it was found that numerous flakes of average size had a maximum length of from one-eighth to three-sixteenths of an inch, but it is to be understood that this illustration is given merely as an example of workable sizes of flakes, and that the flakes may be varied somewhat from these sizes, depending upon the character of the paper used and of the desired product. The passage through the screen is facilitated by the churning action within the disintegrator and by the suction produced by the motor driven fan 8 which blows the air together with the sifted parti-

cles floating thereon through conduit 9 in the direction shown by the arrowed line, the particles being discharged into the large storage hopper 10 which may have the glass top section 11 for inspecting the contents of the hopper.

Paddle wheel 12, located near the lower part of hopper 10, rotates to mingle the particles in the hopper, and aids their movement toward paddle wheel 13, which slowly rotates to periodically discharge definite quantities of the particles into the trough-like conduit 14, connecting with conduit 15, discharging into the rotating fan blower 16, which draws a strong current of air through conduits 14 and 15, and then blows it into conduit 17 in the direction indicated by the arrowed line.

The particles of disintegrated paper float along with the air stream into conduit 17, and are discharged into the upper part of hopper 18, which has the inner walls 19 and 20 converging toward each other. The opening between the lower ends of walls 19 and 20, is substantially closed by the feed roll 21, which slowly rotates in a counter-clockwise direction and has a multiplicity of short projecting teeth 22, extending from the periphery thereof, to engage the particles in the hopper and feed them as a stream down the inner wall 19. The thickness of this stream is controlled by rotation of the hand screw 23, threaded into the outer wall of hopper 18, thereby adjusting the position of wall 19 relatively to feed roll 21. Paddle wheel 24, placed closely above roller 21, rotates to churn the particles in hopper 18, and aids the movement of the particles toward roller 21.

Air entering hopper 18 from conduit 17, discharges through the coarsely woven cover 25 of burlap, or other suitable material, adapted to prevent escape of the particles. When the hopper becomes completely filled, the right hand end of conduit 17 is closed by the accumulation of particles therein, and the current of air and particles is automatically shunted away from hopper 18 through the upright conduit 26, which discharges through conduit 27 into the top of hopper 10, thus preventing the production of excessive pressure within hopper 18, and tending to maintain a uniform stream of particles from roller 21. As long as the passageway into hopper 18 remains clear, the stream of particles from conduit 17 sweeps into the hopper without appreciable loss through conduits 26 and 27. A rapidly rotating toothed wheel 28 near the discharge end of hopper 18, thoroughly intermingles the particles as they leave the hopper.

A roll 29, of relatively thick flexible sheet fabric 42, such as paper, rotates on shaft 30, and a roll 31 of relatively thin flexible sheet fabric 43, such as paper, rotates on shaft 30

22 The two-sheet strips 42 and 43, progressively advance longitudinally over freely rotatable rollers 33 and 34. A deposit of cementitious material such as shellac, sodium silicate, glue, or other suitable material, preferably in thin liquid form to facilitate the production of minute droplets, is deposited on the inner surfaces of the sheets. The sprays 35 and 36, produced by the banks 10 of nozzles 37 and 38 directing atomizing blasts of air past the nozzles 39 and 40, which discharge cementitious material, may be employed for producing the deposit of cementitious material on sheets 42 and 43.

15 The particles discharged as a stream 41 from hopper 18, fall freely through the air, and are deposited as a soft cushioning layer on and between the confluent sheets 42 and 43. The particles in layer 41, adhere as a 20 coating to the sheets 42 and 43 and the combined laminations pass between rollers 33 and 34. The beating of the dry paper, in conjunction with the selection of the particles by screen 7, produces such a quantity of 25 separate fibers 61, Fig. 4, as to form a soft wadding between flakes 60, Figs. 2 and 3, when thoroughly mingled together, as in stream 41.

It has been found desirable in many cases, 30 to so position rollers 33 and 34 in relation to stream 41 that the particles fall more directly upon sheet 43 than upon sheet 42, or so that the particles are first carried on sheet 43 by first adhering thereto. The particles 35 deposited upon sheet 43 then feed into cementing contact with sheet 42 between rollers 33 and 34. It will be noted in Fig. 1, that stream 41 is shifted slightly to one side of the gap between rollers 33 and 34 so that 40 the particles fall more directly toward sheet 43 than sheet 42.

The cushioning layer 41, after passing between rollers 33 and 34 is split medially of the layer, by feeding sheets 42 and 43 away 45 from each other, over freely rotatable rollers 44 and 45, the sheets 42 and 43 being then converged toward each other again. The cleavage surfaces of the fissure produced in layer 41 are then given a deposit of minute 50 cementitious droplets by the sprays or clouds of droplets 46 produced by a bank of nozzles 47, directing blasts of air past nozzles 48, discharging cementitious material. The two sections of layer 41 are then restored into 55 face to face contact with each other by feeding the combined laminations between freely rotatable rollers 49 and 50. Driving rolls 51 and 52 progressively advance sheets 42 and 43 with layer 41 therebetween, and temporarily compress the cushioned laminations 60 to facilitate the cementing of the particles and layers. The pressure of roll 52 toward roll 51, is controlled by rotation of nuts 53 threaded on screw bolts 54 fast to the frame 65 55. Nuts 53 vary the compression of helical

springs 56, pressing on the bearings of roller 52.

The shear blade 57 rotating on shaft 58 in a counter-clockwise direction, cooperates with the fixed shear blade 59 to cut the finished cushioned product into pieces of desired length, a sample of such a piece being shown in Fig. 6. It will be noted that the sheet 42 is represented in Fig. 1, as being appreciably thicker than sheet 43, but it is 75 to be understood that the thickness of either sheet may be varied between wide limits according to the desired use of the finished product.

In Fig. 6 the flakes 60 will be seen to be in 80 interlocking or dovetailed relationship with each other. The separate fibers 61 form soft wadding between the flakes and are locked in place by flakes 60, as well as by the cementing bond with the sheets 42 and 43, and between the particles in the vicinity of the sheets and of the cleavage surfaces of the fissure in layer 41. The beating, churning and mingling of the dry particles tend to produce 85 curls and kinks therein, thus improving their 90 cushioning and interlocking characteristics.

Owing to the different sizes, shapes, and positions of the particles making up cushioning layer 41, and the method by which the cementitious material is applied to the particles, portions only of the cementable parts of the particles are bonded together, and as a result, the particles are free to bend and slide on one another between their cemented 95 portions, so that the desired cushioning characteristics may be obtained. The loose cellular structure between the uncemented portions of the particles, in view of the low thermal conductivity of the material of the particles, provides relatively high thermal 100 insulation. By leaving portions of the particles uncemented, the natural springiness of the particles is preserved to a large extent, and an efficient and durable cushioning and insulating product is produced. The cushioned pad of Fig. 6, has been found to be 105 particularly adapted for use in the paper box industry especially in making the cushioned tops of candy boxes, and is also useful as a sheathing paper, and as insulation 110 against the transmission of sounds and heat or cold, or for packing. The method of making the cushioned product is simple, and of low cost, while the materials employed are readily obtainable in large quantities at low 115 cost in comparison with other available materials.

After splitting the cushion layer 41, the resulting laminated units consisting of sheets 42 and 43, respectively, with their adhered 120 cushioned layers, may be separately utilized, similarly to the product shown in Fig. 6, without cementing the laminations together between rollers 49, 50, 51 and 52.

Instead of cementing the particles in 125

stream 41 to sheets 42 and 43 they may be discharged from hopper 18 and used in bulk for cushioning and insulating purposes, the flakes 60 functioning similarly to those shown in Fig. 6.

Fig. 7 shows a modification of the machine of Fig. 1 between rollers 33 and 34, and rollers 49 and 50, the third sheet 62 of flexible fabric, such as paper, being fed from roll 63, free to 10 rotate on shaft 64. Sheet 62 feeds between the cleavage surfaces of the fissure produced in layer 41, thereby producing a bonding element between the two sections 65 and 66 of the cushioning layer.

15 Banks of spraying nozzles 67 and 68, respectively, deposit cementitious material on the cleavage surfaces of layer 41 and at the same time on the two surfaces of sheet 62, so that the combined laminations passing between rollers 49 and 50 are cemented together 20 as a single unit. The resulting product possessed greater strength than that of Fig. 6, and may be used similarly thereto.

25 The machine of Fig. 8 has the input hopper 1, into which is placed the dry paper to be disintegrated. The disintegrator 2, has a rotor 69 constructed somewhat differently from that shown in Fig. 1. The shaft 3 has the radial disks 4 keyed fast thereto, Fig. 9. 30 Pairs of disks 4 support the fixed shafts 70, upon which are freely swivelled the arms 71, having bifurcated outer ends. Between each pair of ends, is supported the notched hammer disks 72, freely rotatable on pivots 73.

35 The paper is disintegrated by high speed rotation of rotor 69, and particles below a predetermined small size, driven by the churning action of rotor 69, discharge through conduit 74, into hopper 75, having 40 the inner wall 76. Disintegrated particles, consisting of flakes and fibers, discharge through the gap between the lower end of wall 76 and the wall of hopper 75, and are deposited on the top of feed roll 77, having 45 the small projecting teeth 78. Roll 77 rotates slowly, as shown by the arrow, and feeds a loose stream of particles 79 from the hopper, allowing the particles to fall freely through the air in more or less spaced-apart 50 relationship into the bottom of the V-shaped trough, formed by the sheets 42 and 43, of flexible fabric, such as the paper in sheets 42 and 43, Fig. 1. Sheets 42 and 43 feed longitudinally into confluence between driving 55 rollers 51 and 52. The particles in stream 27, feed through a fog like cloud 84 of cementitious droplets, formed by nozzles 85 discharging compressed air from blower 88, past nozzles 86 which discharge cementitious 60 material from the reservoir 87.

A valve 83 for each of the nozzles 85 and 86, is adjusted so that the cementitious liquid is very finely divided into droplets which tend to float on the air as a fog-like cloud and 65 become deposited on the particles in stream

79 passing therethrough. By making the droplets very fine a cementitious deposit can be produced with less blowing of the particles from their proper positions in stream 79 than when the spray is deposited with force 70 on the freely falling particles. An advantage of this method of applying the cement to the particles in stream 79, is that the cement tends to deposit in spaced apart 75 relationship on the particles, so that portions only of their cementable parts eventually become cemented together. At the same time, sheets 42 and 43, which confine the droplets in cloud 84, to the region of stream 79, receive a deposit of cementitious material. 80

The particles in stream 79 are brought together between sheets 42 and 43, and form the cushioning layer 80. The pressure of roll 52 toward roll 53 aids the cementing of the particles, and of the layer 80 to sheets 42 and 85 43, thus producing an efficient cushioning or insulating unit.

Fig. 11 shows a form of apparatus adapted for producing and depositing minute cementitious droplets, and particularly for 90 depositing the droplets on the particles of disintegrated paper in stream 79, with minimum disturbance to the positions of the particles. The casing 89 is partly filled with the thin liquid cementitious material 90, forming 95 a pool in the lower portion of the casing. A roller 91, dipping tangentially into the liquid 90, rotates in a clockwise direction, and carries an adhered coat of the liquid 90 on its periphery. Any excess of the liquid on roller 100 91 is removed by the wiper 92, which also helps to spread the liquid so that a film of uniform thickness remains on the roller. A shaft 93, rotating at high speed in a counter-clockwise direction, has the bristles or stiff 105 wires 94, extending radially therefrom. The outer ends of bristles 94 brush over the periphery of roller 91, and throw off a spray 95 of minute droplets of the cementitious liquid, these droplets forming a fog-like cloud 96, 110 in the vicinity of stream 79, so that the droplets become deposited on the particles of disintegrated paper, somewhat similarly to a deposit of dew. The apparatus shown in Fig. 11, may obviously be utilized for depositing 115 cementitious material, in place of any of the spraying or atomizing apparatus shown in Figs. 1, 7 and 8.

Various modifications of the details described herein as illustrative of the invention, will be apparent to those skilled in the art, without departing from the principles disclosed herein. For example, variations may be made in the thickness and character of the fabric or material employed in the backing sheets, or in the number and thickness of layers in the product. Obviously, a finished laminated sheet, such as produced by the method of Figs. 1, 7, or 8, may be fed into the machines in place of sheet 42, thus making 120 125 130

additional cushioning layers in the final product, to produce a product of greater thickness, having greater cushioning and insulating characteristics than that of the product shown in Fig. 6.

The method and machine are not claimed herein, being claimed in our co-pending application Serial No. 524,514, filed March 23, 1931, which is a division hereof.

10. We claim:

1. A cushioned fiber product consisting of a layer of particles of partially disintegrated paper and other particles of substantially completely disintegrated paper intermingled therewith in such quantity as to form a thin wadding interlocked between said first particles, and a closure for said layer comprising sheets of fabric on opposite sides of the said layer, said layer being cemented to the closure.

2. A fiber product consisting of relatively short fibers grouped together as a soft wadding, and relatively small paper flakes of greater length than said fibers, dispersed throughout said wadding in interlocking relationship with each other and with said wadding.

3. A laminated fiber product having a layer of sheet fabric, and a cushioning layer cemented thereto consisting of particles of partially disintegrated paper and other particles of substantially completely disintegrated paper intermingled with said first particles as a soft wadding.

4. A laminated fiber product having a layer of sheet fabric, and a cushioning layer cemented thereto, consisting of separate fibers of disintegrated paper and relatively small flakes of paper intermingled with said fibers, said fibers and flakes being cemented together at portions only of their cementable parts.

5. A cushioned pad having two layers of sheet fabric, and an intermediate layer consisting of relatively short fibers grouped together as a soft wadding and having relatively small paper flakes of greater length than said fibers, dispersed throughout said wadding in interlocking relationship with each other and with said wadding, said intermediate layer being cemented to said fabric layers.

6. A laminated fiber product having two layers of sheet fabric, and an intermediate cushioning layer consisting of particles of disintegrated paper disposed between said fabric layers and cemented thereto, said intermediate layer having a medial fissure, produced by longitudinally splitting the layer after said layer is cemented to said fabric, the registering faces of said fissure being bonded together.

7. A laminated fiber product having two layers of sheet fabric, each having a cementitious face and having a separate cushioning layer of disintegrated paper deposited as

separate particles into cementing relationship with said face, the outer faces of said disintegrated paper layers being disposed in face to face contact with each other and cemented together.

In witness whereof, we hereunto subscribe our names, this 7th day of May, 1928.

AUGUST GERARD.
MAURICE WEISMAN.
